UNITED STATES PATENT OFFICE.

WILBERT A. HEYMAN, OF NEW YORK, N. Y., ASSIGNOR TO HEYMAN PROCESS CORPORATION, OF NEW YORK, N. Y.

DESIGN FOR A BOTTLE.

Application filed April 8, 1927. Serial No. 21,507. Term of patent 14 years.

To all whom it may concern:

Be it known that I, WILBERT A. HEYMAN, a citizen of the United States, residing at New York, in the county of New York and State of New York, have invented a new, original, and ornamental Design for Bottles, of which the following is a specification.

The figure is an elevation view of a bottle, showing my new design.

I claim:

The ornamental design for a bottle, substantially as shown.

Signed at New York, in the county of New York and State of New York, this 25 day of March, 1927.

WILBERT A. HEYMAN.
